UNITED STATES PATENT OFFICE.

TAUBE DAVIS, OF NEW YORK, N. Y., ASSIGNOR TO FRANKLIN SIMON & CO., INC., OF NEW YORK, N. Y., A CORPORATION OF NEW YORK.

DESIGN FOR A LADY'S SUIT.

Application filed July 31, 1924. Serial No. 10,332. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Lady's Suit, of which the following is a specification, reference being had to the accompanying drawing, forming part thereof.

The figure is a perspective view of a lady's suit, showing my new design.

The essential features of my design comprise a coat with a double breasted effect having a double row of buttons near the

bottom and a widely spread collar effect with one lapel extending to near one row of buttons, a pair of pockets at the lower edge distinguished by vertically arranged spaced plaits agreeing in appearance with an elongated section forming the neck opening, which section is distinguished by spaced plaits extending at right angles to its length, the strip being ornamented on one edge by a conventionalized representation of fur.

I claim:

The ornamental design for a lady's suit, substantially as shown and described.

TAUBE DAVIS.
